Section 1, Public Law 690, August 8, 1946
Patent expires June 27, 1965

2 Claims. (Cl. 179—171)

1

The copending patent application, U. S. Serial No. 683,710, describes a circuit arrangement for amplifying electrical oscillations by means of at least two parallel-connected grid-controlled discharge paths having characteristic curves whose mutual conductance varies as a function of the control-grid voltage. This circuit exhibits the feature that discharge paths are used, one of which has a comparatively high average mutual conductance and a comparatively small grid space, whereas the other has a comparatively low average mutual conductance and a comparatively large grid space, means being provided which bring about automatically that the amplification, with small amplitudes of the oscillations to be amplified, exclusively or almost exclusively takes place by the first mentioned path and, in the case of large amplitudes of these oscillations, exclusively or almost exclusively by the last-mentioned path.

Automatic changing over from one discharge path to the other can be secured effectively by supplying to the control grids a control voltage which depends upon the amplitude of the oscillations to be amplified, this control voltage blocking the first-mentioned discharge path at comparatively high values of the oscillations to be amplified and at the same time affects the potential of an auxiliary electrode located in the last-mentioned discharge path (i. e. the path having the comparatively low average mutual conductance and the comparatively large grid space) in such a manner as to block this path at comparatively small values of the oscillations to be amplified.

In a constructional form of the circuit arrangement, which is set out hereinafter, the said auxiliary electrode is connected through a resistance to the interconnected anodes of the two discharge paths, the common anode circuit of these paths including a preferably high resistance having such a value that the discharge path, in which the auxiliary electrode is located, is blocked in the case of small amplitudes of the oscillations to be amplified.

The present invention has for its object to provide an improvement of this circuit arrangement, by which the maximum obtainable amplification is increased.

The invention is based on the realisation that the said resistance, which is placed between the auxiliary electrode and the anodes, reduces the anode impedance and consequently the amplification.

According to the invention the said auxiliary

2

electrode is connected through a resistance to a grid (screen grid) which is located in the first-mentioned discharge path and to which a positive voltage is supplied through a resistance, the said resistances being given such a size that the discharge path, comprising the auxiliary electrode is entirely or almost entirely blocked in the case of comparatively small amplitude of the oscillations to be amplified.

It has been found, in effect, that for blocking the last-mentioned discharge path it is not necessary to connect the auxiliary electrode to the interconnected anodes of the two discharge paths. It turned out that the cutting out of this discharge path can take place also if the voltage for the auxiliary electrode is taken from a grid having a positive voltage in the other discharge path. Preferably, the auxiliary electrode and the grid having a positive voltage are chosen in such a manner that the influence of the auxiliary electrode on the associated control grid is greater than the influence of the grid having a positive voltage on the control grid in question.

In order that the invention may be clearly understood and readily carried into effect it will now be set out more fully with reference to the accompanying drawing given by way of example.

The drawing represents a circuit arrangement for amplifying low frequency oscillations, comprising two discharge paths both of which are mounted in a single discharge tube 1. This tube comprises a control grid 2, a screen grid consisting of two parts 3, 3', a suppressor grid 4, an anode 5 and a cathode 6 which is connected to the suppressor grid 4. The aforesaid auxiliary electrode is constituted by the part 3' of the screen grid. The discharge path comprising this auxiliary electrode is controlled by a part of the control grid having an uneven winding pitch, the control grid portion located in the other discharge path having a constant winding pitch. The two control grid parts are directly connected electrically. The suppressor grid 4, the anode 5, and the cathode 6 serve simultaneously for the two discharge paths.

The screen grid part 3 is connected, through a resistance 8, to the positive terminal of a source of direct voltage (not represented) and through a condenser 9 to the cathode 6.

According to the invention the auxiliary electrode 3' is connected to the screen grid portion 3 through a preferably high resistance 10. Moreover, the auxiliary electrode is connected to the cathode 6 through a condenser 11. The anode

3

circuit includes a comparatively high resistance 12.

The low frequency oscillations to be amplified are supplied, jointly with a control voltage depending upon the amplitude of these oscillations, to the control grid 2. The amplified oscillations can be taken from the resistance 12 through the intermediary of a condenser 13.

The circuit arrangement yields the same effect as that according to the copending patent application, heretofore mentioned, i. e. a high maximum, noiseless amplification (with a low anode current) if the amplitude of the oscillations to be amplified is comparatively small, and an amplification which is well regulable if this amplitude is comparatively large. The high maximum amplification is obtained by means of the discharge path comprising the screen grid part 3, the regulable amplification being obtained by means of the discharge path comprising the auxiliary electrode 3'.

However, the automatic changing over from one discharge path to the other takes place, at least partly, in a manner which is different from the aforesaid constructional form of the circuit described in the copending patent application, heretofore mentioned. With a large amplitude of the oscillations to be amplified, consequently at a high negative value of the control voltage, the right-hand discharge path is cut off by the control voltage supplied to the control grid 2, whereas the left-hand discharge path keeps functioning. With a small amplitude of the oscillations to be amplified, and consequently at a low negative value of the control voltage, the right-hand discharge path keeps functioning, whereas the left-hand discharge path is entirely or almost entirely blocked. This blocking takes place as follows: In the case of a decrease in negative value for the control voltage the current of the screen grid 3 increases, with the result that the positive voltage of this grid and consequently also the voltage of the auxiliary electrode 3' decreases, since the increased screen-grid current contributes to the voltage loss through the resistance 8. However, the voltage of the auxiliary electrode 3' assumes a value which is even smaller than the voltage of the screen-grid 3, because the current flowing to the auxiliary electrode brings about a voltage loss through the high resistance 10. Since the influence exerted by the auxiliary electrode in the control grid part having an uneven winding pitch, is greater than the influence of the screen grid in the control-grid part having a constant winding pitch, the voltage drop of the auxiliary electrode involves a decrease in current strength of the left-hand discharge path and consequently of the current flowing to the auxiliary electrode. By a suitable choice of the resistances 8 and 10 it is ensured that the voltage of the auxiliary electrode 3' drops to such a degree that the discharge path in question practically no longer contributes to the current and consequently to the amplification.

In a practical construction of the present arrangement the resistance 8 has a value of 1 meg-ohm, the resistance 10 having a value of 1.5 meg-ohm. The influence of the auxiliary electrode 3' on the control grid 2 exceeds that of the screen grid 3 on the control grid 2 (about 0.1 and 0.02 respectively). In the following table the values of the screen-grid current I_3 of the current I_3 , flowing to the auxiliary electrode, of the screen-grid voltage V_3 and of the voltage of the auxil-

4

iary electrode V_3' are stated for two values of the control voltage (viz. 0 volt and -5 volts). Control voltage=0 volt.

5                     $I_3=300$ milliamperes $V_3=100$ volts
                   $I_3'=50$ milliamperes $V_3'=25$ volts

Control voltage=-5 volts

10                   $I_3=0$ milliamperes $V_3=310$ volts
                   $I_3'=140$ milliamperes $V_3'=100$ volts

15   From this table clearly appears that in the controlled state (control voltage=-5 volts) exclusively the left-hand discharge path conveys current, whereas the right-hand discharge path is cut off, and that in the non-controlled state (control voltage=0 volt) the amplification mainly takes place by the right-hand discharge path, the left-hand discharge path being substantially entirely cut out.

20   The present circuit arrangement has the advantage over the arrangement set out in the copending patent application, heretofore mentioned, that the anode impedance may have a high value, since the resistance 10 is no longer connected to the anode 5.

What I claim is:

1. An amplifying circuit arrangement to couple a source of desired signals to an output stage comprising, first and second thermionic discharge paths enclosed in an evacuated envelope, said paths being connected in parallel relation and having common cathodes and anodes, the first thermionic discharge path having further a control grid electrode with given spacing and transconductance and a screen grid electrode, the second thermionic discharge path having further a control grid electrode with larger grid spacing and lower transconductance than the control grid of the said first thermionic discharge path and an auxiliary electrode between the control grid of the said second thermionic discharge path and the common anode, means to couple the source of desired signals to the cathode-control grid circuits of the said first and second thermionic discharge paths, a first resistive element connected between said auxiliary electrode and said screen grid electrode, and a second resistive element connecting the said screen grid electrode to a source of direct current potential; said first and second elements having respective values at which said second path is rendered non-conductive when the signals applied to said first and second paths attain a relatively low amplitude level.

55   2. An amplifying circuit arrangement comprising a source of desired signals, an output stage, first and second thermionic discharge paths enclosed in an evacuated envelope, said paths being connected in parallel relation and having common cathodes and anodes, the first thermionic discharge path having further a control grid electrode with given spacing, transconductance and constant winding pitch and a screen grid electrode, the second thermionic discharge path having further a control grid electrode with larger grid spacing, uneven winding pitch and lower transconductance than the control grid of the said first thermionic discharge path and an auxiliary electrode between the control grid of the said second thermionic discharge path and the common anode, means to couple the control grids of the said first and second thermionic discharge paths, means to connect 75 said source of desired signals to the control grids,

a first resistive element connected between said auxiliary electrode and said screen grid electrode, and a second resistive element connecting the said screen grid electrode to a source of direct current potential, said first and second elements having respective values at which said second path is rendered non-conductive when the signals applied to said first and second paths attain a relative low amplitude level.
